HAIR CUTTING APPLIANCE

Glenn C. Mitchell, Aurora, Ill.

Application February 1, 1945, Serial No. 575,607

5 Claims. (Cl. 30—30)

1

This invention relates to improvements in appliances for cutting hair.

The primary object of this invention is the provision of a hair cutting comb comprising a comb portion and a hair cutting blade so associated therewith as to most efficiently cut hair under a variety of circumstances.

A further object of this invention is the provision of an improved combination comb and hair cutting blade; the latter being so related to the comb as to permit of the most efficient disposal of the cut hair.

A further object of this invention is the provision of an improved arrangement for the application of a cutting blade to a comb.

A further object of this invention is the provision of an improved cutting blade adapted to be associated with a comb.

A further object of this invention is the provision of improved means for attaching a cutting blade to a comb and positioned to cut the hair and in another position to permit of the stropping of the blade.

Other objects and advantages of the invention will be apparent from the following detailed description.

In the accompanying drawing wherein for the purpose of illustration is shown only a preferred embodiment of the invention—

Figure 1 is a side elevation of the comb having the improved blade associated therewith in cutting position.

Figure 2 shows the association of the blade upon the comb to permit the stropping of the blade.

Figures 3 and 4 are enlarged cross sectional views taken substantially on the respective lines shown in Figure 1 of the drawing.

Figure 5 is a side elevation of the preferred construction of the blade.

In the drawing, wherein similar reference characters designate corresponding parts thruout the several views, the letter A may generally designate the combination comb and cutting blade which consists of a comb B and a cutting blade C.

The comb B may be made of hard rubber, plastic or any other desired material. It includes a solid back portion 10 having teeth 11 extending transversely therefrom. The comb in height is tapered from one end to the other, and as shown in the cross sectional view in Figure 4 the teeth 11 taper in thickness from the back 10 towards the scalp engaging ends of the teeth. The teeth may extend from end to end of the comb or be provided in any desired arrangement upon the back of the comb. The back of the comb is pro-

2

vided with a pair of definitely spaced screw threaded openings 13 and 14 therein for the detachable reception of blade attaching screws 16.

The blade C is of steel and has a tapered cutting edge 20 thereon. The blade is preferably of uniform thickness from side edge to side edge and from top edge to the cutting edge 20, the latter being beveled to provide a taper at both sides thereof so that notwithstanding which side 10 of the blade is against the comb, the cutting edge will be slightly spaced from the side surface of the teeth 11, as shown in Figure 4.

The blade C is provided with semi-circular notches 21 at each side edge thereof closer to the top edge 22 than the cutting edge and in a definite relation so that when the shanks of the screws 16 are received in these notches 21, the cutting edge of the blade will lie over the teeth of the comb in definitely spaced relation from the free ends of the teeth, as shown in Figure 1 of the drawing. The blade C includes an opening 24 at one end thereof which is adapted to receive a hook or other support, so that a number of the blades can be carried in close proximity to a barber. Otherwise the blade is provided with an area designated at 25 by dot and dash lines in Figure 5 wherein openings are to be made. These openings are definitely located upon the blade so that they will lie over the teeth 11, and not cover the back 10 of the comb. Their function is to permit loose hairs to pass therethru so that the comb may be maintained in a clean condition. This open area 25 may be fully opened or portions thereof may bridge the width of the opening 30 to provide reinforcement for the comb. If desired, the openings may take the form of initials or any other characters desired, as shown in Figures 1 and 2.

In the application of the blade upon the comb it will be noted from Figures 3 and 4 that the blade is maintained by the screws 16 flat against the teeth 11 and the back of the blade at the tapered or cutting edge 20 slightly spaced from the teeth so as to permit of an efficient shearing effect upon the hair. While in the drawing the cutting edge of the blade has been shown parallel with the free end of the teeth, the cutting edge at this point may be sloped at an acute angle with respect to the free edge line of the teeth, so that a shearing effect may be provided as the comb is used.

To remove a blade, it is merely necessary to loosen one screw slightly and remove the other screw completely. The blade will not slip longitudinally or transversely and it cannot be re-

moved unless one screw is completely removed. This assures accuracy in cutting and positioning of the blade at all times.

The blade C can be reversed in its position with respect to the back of the comb, so that the cutting margin of the blade is extended beyond the marginal edge of the back of the comb, as shown in Figure 2, to permit stropping of the blade.

In the cutting of hair, if the barber or individual has the blade positioned towards the scalp with the teeth outermost, the appliance will cut hair deeper. If the teeth portion of the comb are between the scalp and the blade the latter will cut hair quite shallow. The cutting is gradual and will not notch the hair.

Due to the efficient arrangement of blade and comb, the device may be used for stripping, as well as wave cutting. For "ruffing" the hair, in order to produce a wave, the individual performing the operation will lift up the longest locks of hair. From underneath these locks the hair will be notched with the cutting comb in a wave-like fashion. The hair will then be carefully pressed firmly to the scalp and again the operation will be repeated. It has been found that a repetition of cutting the hair in this fashion for about four hair cuts will provide a permanent wave which may be easily maintained.

Since the screw threaded openings extend completely thru the back of the comb, it will be noted that the blade may be applied upon either side of the comb.

Various changes in the shape, size and arrangement of parts may be made to the form of invention herein shown and described, without departing from the spirit of the invention or the scope of the following claims.

I claim:

1. A hair cutting appliance comprising a comb having a back portion and teeth extending therefrom, a cutting blade, and means on the back of the comb for detachably engaging the opposed side margins of the blade for removably holding the blade in operating relation with respect to the teeth of the comb.

2. In a cutting appliance the combination of a comb having a back portion and teeth, a flat cutting blade having a cutting edge and an opening providing zone thereacross, and means for connecting the blade upon the comb with the cutting edge in operating relation with respect to the teeth of the comb and the opening zone facing the teeth to permit passage of detached hair therethru.

3. In a cutting appliance the combination of

a comb including a back and laterally extending teeth, a safety razor type of cutting blade, and means for connecting the blade upon the back of the comb with the cutting edge of the blade facing the teeth of the comb, said means permitting removal of the blade and attachment with its cutting edge extending in an opposite direction beyond the back of the comb for the stropping thereof.

4. In a hair cutting and combing appliance the combination of a comb comprising a back portion and laterally extending spaced teeth, a flat substantially rectangular-shaped cutting blade having a straight line cutting edge at one longitudinal edge thereof, means for clamping the blade upon the back portion of the comb with the cutting blade extending laterally over and in engagement with the teeth and at its cutting edge being spaced in a line inwardly from the outer free ends of said teeth, said cutting blade being transversely apertured along the line of connection of the teeth with the back of the comb and extending over a small area along the teeth whereby to permit passage of severed hair therethrough.

5. In a hair cutting appliance the combination of a comb including a solid back portion and laterally extending teeth connected therewith, said back portion having a pair of predeterminedly spaced screw threaded openings therein, a substantially rectangularly-shaped cutting blade having recesses inwardly from the opposite edges thereof and opening upon said edges, said screws being adapted to fit in said recesses to hold the blade in cutting relation against the comb, said blade having a cutting edge and being of a size to space the cutting edge inwardly from the outer ends of the comb teeth when the blade is in position upon said comb, said blade being transversely apertured therethrough at a zone immediately overlying the teeth at their base connection with the back of the comb whereby to permit passage of cut hairs therethrough and prevent clogging.
